UNITED STATES PATENT OFFICE.

PERRY S. MARTIN, OF HARRISONBURG, VIRGINIA, ASSIGNOR TO NEWTOWN GIANT INCUBATOR CORPORATION, OF HARRISONBURG, VIRGINIA, A CORPORATION OF VIRGINIA.

HYDROCARBON BURNER.

Application filed November 9, 1920. Serial No. 422,913.

To all whom it may concern:

Be it known that I, PERRY S. MARTIN, a citizen of the United States, residing at Harrisonburg, in the county of Rockingham and State of Virginia, have invented certain new and useful Improvements in Hydrocarbon Burners; and I do hereby declare the following to be a full, clear, and exact description of the same, reference being had to the accompanying drawings, forming part of this specification.

This invention relates to liquid burning devices as for example, a burner suitable for use with hydrocarbons such as kerosene, and has for its object the provision of means permitting maximum efficiency of the burner when at less than half capacity as well as at full capacity. A further object of the invention lies in the provision of a burner having a delicate temperature regulation, but in which the burner and the oil fount are both stationary, the regulation being accomplished by movement of a flexible friction tube leading from the fount and delivering the fluid drop by drop past a sight window in the oil tank casing. Other objects of the invention will be apparent from the following description taken in connection with the claims.

In the drawings,—

Figure 1 is a plan view of one form of my device;

Fig. 2 is a general elevation largely in vertical cross section;

Fig. 3 is a horizontal sectional view on the line 3—3 of Figure 2;

Fig. 4 is a plan view of the burner bowl; and

Fig. 5 is a plan view of the base for the oil fount and casing.

The invention described in the following pages is not to be considered as limited to a burner for any particular use, the inventive concept being adaptable to a great variety of uses. In the drawings a form of my device is illustrated which has been manufactured for use with a brooder and the following description, of the base for example is merely for illustration, and not as a limitation, it being the intention to limit the scope of invention only as required by the claims.

The base 10 will be generally be of solid material serving merely as support for the various parts, but when used in connection with a brooder, it is preferred that the base

should be open at the bottom but closed at the sides 11 and ends 12, so as to form a passage or chamber when placed upon the ground, the entrance to such chamber being through the orifice 13 beneath the reservoir, and the exit being a similar orifice 14 directly beneath the center of the cover. The chimney 15 is a cylindrical tube serving the dual function of supporting the fuel reservoir and associated parts and of supplying air to the chamber beneath the base 10, the casing being provided with holes 16 and 17 for this purpose and for the reception of the oil pipe 18 leading from the drip cup 19 to the burner bowl 20. The reservoir 21 rests upon the upper reinforced edge 22 of the oil fount so as to be protected by the casing 23 and has an outlet 24 extending into the oil fount 25 thereby maintaining the oil at the level of the bottom of such outlet. The reservoir 21 is provided with the usual cork valve 27 connected to a rod 28 of greater than the distance from the cork to the base 29 of the casing and fount, so that when the reservoir is placed on the fount the cork will be driven inward allowing oil to flow from the reservoir until it closes the mouth of the orifice 24, thereafter maintaining such level constant in the well known manner. The base 29 of the casing may be supported in any desired manner, as for example, by means of the tie rods 30 extending to a bar 31 extending transversely across the base 10 thereby firmly binding the base 29 against the chimney 15.

A small flexible friction tube 35 extends through the oil fount 25 as at 36, making an oil tight junction, and extends upwardly in a helical line between the fount and casing and ends after a complete revolution or more in a downturned spout 37 directly above the oil cup 19, the spout preferably being centrally located with respect to the mica window 38 closing a corresponding orifice in the casing 23. A small bracket 40 is secured to the side of the casing 23 and furnishes a pivotal support 41 for the drip regulating lever 42 as well as threaded supports for the adjusting screws 44 and 45 governing respectively the minimum and maximum flow of oil through the flexible tube 35.

The supply of oil to the burner is controlled by a thermostat 48 of the usual form, preferably of the circular corrugated double convex ether-alcohol type, secured to a

bracket 49 clamped by the oil pipe 18 by means of the bolts or other fastenings 50. While the thermostat is shown in Figures 1 and 2 as in close proximity to the burner, it will readily be understood that this thermostat will be located in the region most convenient for temperature regulation and when used with a brooder, for example, will be located as shown in Figure 1 of my co-pending application No. 422,914, filed this day. The particular form of thermostat forms no part of the invention and would vary in accordance with the use to which the burner is put, and would, for example, be located within the water tank if the burner were used to maintain a body of water at constant temperature. A thermostat lever 51 is hinged to the bracket as at 52 and is normally held against the umbo 53 of the thermostat by means of the action of a weight 54 swung from the regulating lever 42 on the tube side of the pivot 41 and operating by adding its weight to that of the tube 35 to swing the lower end of lever 42 away from the thermostat bracket, but owing to the connection 55 between such lower end and the lever 51 serving to hold the latter in contact with the thermostat umbo.

As the temperature increases the thermostat expands and pulls the lower end of the drip regulating lever 42 to the left against the action of the weight 54 and raises the end of the tube 35 until the short arm of the lever comes into contact with the minimum adjusting screw 44 when further increase in temperature will be accommodated merely through the bending of the relatively long levers 42 and 51. The minimum adjusting screw 44 is usually set to provide just sufficient flow of oil to operate the burner and the maximum adjusting screw is normally set so that the greatest quantity of oil will be furnished that can be taken care of by the burner. These regulating screws are not made permanent for obvious reasons including the need for a very rapid flow on first using the brooder for example and the necessity of entirely closing the flow when desired, which is accomplished by turning the minimum screw 44 so as to bring the spout 37 entirely above the surface of the oil in the fount 25.

The burner bowl 20 is secured to the oil pipe 18 and is supported at the proper elevation by means of a bracket 60 secured to the base 10 and so arranged that there should be a slight slope to the oil pipe from the bend where it enters the chimney 15 down to the burner bowl in order to insure a proper flow of oil.

The burner bowl is a flat annular casting having a boss 62 threaded to receive the end of the pipe 18 and a central orifice 63 bounded by the vertical flange 64 which forms one wall of the trough 65, the other

wall being formed by the outwardly sloping external flange 66. The flange 66 has a slight groove 67 in its upper inner face to furnish a secure support for the outer perforated combustion tube 68. The inner flange 64 may likewise be grooved on its upper outer face to receive the inner perforated combustion tube 70, but it is preferred that the latter should have a friction fit with the outer face of the inner flange and have the lower points of its vertical cleats 71 abutting the partitions 72 in the trough. This abutment between the cleat and the partition will not interfere with the flow of oil over the partition, since the cleats 71 are slightly beveled at their lower ends to permit the spilling of oil between the cleat and the outer annular face of the trough.

These partitions 72, which may be two in number as shown, or any number of pairs, serve an important function in the present invention, since they permit the burning of a large or small quantity of oil with equal efficiency, and furnish a most satisfactory substitute for the tilting burner which has the serious disadvantage of smoking and giving off unburned fumes of hydrocarbons from the portion of the trough not supplied with oil since the entire trough is invariably hot. With the simple form illustrated having but the two diametrically opposed partitions, the oil is delivered to the front end of the trough 65 in large or small quantity. If but a small quantity of oil is delivered the flame will be entirely confined to the front half of the burner, since the level of the oil in the trough will not be high enough to overflow the partitions 71. The efficiency of the flame, however, will be just as high as if twice the quantity were delivered, since the level of the oil will be the same and the flame will be confined to the front half of the annular space between the perforated combustion tubes 68 and 70 by virtue of the perforated cleats 71 which extend throughout practically the length of the inner tube 70. When full quantity of oil is used it naturally overflows the partition and both halves of the burner are used in the usual way, the flame then being annular and the entire annular chamber between the tubes being utilized. Thus it will be seen that in the present device a stationary burner is utilized in combination with a stationary oil fount and reservoir, the appropriate flow being maintained by movement of the flexible friction tube 35 alone.

A circular baffle plate 75 is held against the downwardly extending legs 76 of the burner base by means of a tie rod 77 passing through the burner cap 78 and being secured thereto by means of a nut 79 which holds the cap in close engagement with the top of the inner tube 70 which receives the

reduced central projection 80 of the cap. The cowl 81 is of the usual conical shape, has a friction fit with the top of the outer combustion tube 68 and is provided at its lower end with a circular series of air holes 83. The cowl preferably has its flaring skirt somewhat larger than the burner bowl 20, but slightly smaller in diameter than the spreader 75.

10 If the base of the burner is solid the air for combustion will be drawn mainly through the central orifice 63 of the bowl, but in the particular embodiment illustrated, the air which is to be heated for the 15 use of the little chicks and for the burner will be supplied through the holes 16 in the chimney 15 and will pass downwardly through the hole 13 through the passage in the base 10 and upwardly through the orifice 14. It will then be spread by the circular baffle 75, part of the air traveling upwardly alongside of the cowl 81 by which it will be heated and part of it passing inwardly over the spreader and upwardly 25 through the central hole 63 of the bowl and in the space between the cowl and the outer tube. Part of the air in this latter space will pass through the holes 83 and into the hover space while the remainder will pass through 30 the perforations in the tube and aid in supplying oxygen to the flame. The products of combustion will all pass through the annular orifice between the cowl and the cap 78.

35 What I claim is:

1. A burner device consisting of a trough member and transverse partitions in said trough, said partitions in the trough being of less height than the depth of the trough 40 so that liquid from the portion of the trough between any two partitions may overflow into adjacent portions without spilling over the sides of the trough member.

2. In a burner device, an annular trough 45 member having a large central opening concentric with said trough and radial partitions in said trough, said radial partitions being of less height than the depth of the trough so that liquid may spill over a partition without spilling over the sides of the trough.

3. In a burner device, a burner bowl having a trough therein and an inlet to said trough, and transverse partitions in said 55 trough of less height than the depth of the trough but greater than the height of the bottom of the entrance opening.

4. A burner bowl having a relatively 60 large central opening, a trough surrounding the central opening, and an entrance opening to said trough, and a plurality of radial partitions in said trough of less height than the depth of the trough extending at right angles to the axis of said entrance opening.

65 5. An annular burner bowl having an en-

trance opening, an inner vertical wall defining said central opening and forming the inner wall of a fuel trough, an outer vertical wall spaced from said first mentioned wall substantially parallel thereto defining the 70 outer margin of said trough, and integral members connecting said inner and outer walls of the trough to confine small quantities of liquid fuel to the side of the trough nearest the entrance opening. 75

6. In a burner device, a trough member, a plurality of partitions in said trough of less height than the depth of the trough and temperature controlled means for regulating the rate of supply of fuel to said 80 burner.

7. In combination, a non-tilting annular burner and means for confining the flame to a sector of the burner when a small quantity of liquid fuel is supplied and for automatically permitting the flame to extend throughout the burner when the supply of fuel is at a maximum. 85

8. In a burner, concentric perforated inner and outer tubes, means for supporting 90 said tubes, and a plurality of members dividing the annular space between said tubes into a plurality of segments.

9. In a burner, concentric perforated inner and outer tubes, a trough member for supporting said tubes, partitions in said trough and a plurality of members dividing the annular space between said tubes into a plurality of segments, said members registering with said partitions. 95

10. A perforated burner chimney having a plurality of longitudinally arranged radially projecting perforated cleats secured thereto. 100

11. In a burner device, a trough member, 105 an inner member embracing one wall of said trough, an outer member supported by the other wall of said trough and cleats radially projecting from one of said members to divide the annular space between said members into a plurality of segments, and means carried by the trough member for separating the trough into a similar number of trough segments corresponding in size and position with the segments formed by said 110 members and cleats. 115

12. In a burner, an annular trough member having a relatively large central vertical opening and an entrance opening to 120 said trough, radially extending partitions in said trough arranged at right angles to said entrance opening, an inner perforated chimney having radially extending cleats adapted to rest upon said partitions and an outer 125 perforated chimney supported by the outer wall of said trough and cooperating with said inner chimney and cleats to form a plurality of equal semi-circular segments and a cap mounted upon said inner chimney and closing the top thereof. 130

13. In combination, a non-tilting burner, a fuel supply member, means for dividing the burner space into a plurality of sectors one of which may be used independently of the others, and means for regulating the supply of liquid fuel to said burner.

14. In combination, a burner having a trough divided into a plurality of sections, relatively low partitions separating said

sections, means for supplying liquid fuel to said burner at a rate to fill one only of said sections, and heat operated means for increasing the supply of fuel so as to flood other of said trough sections by raising the liquid level in said trough above the height of the first partition.

PERRY S. MARTIN.
